UNITED STATES PATENT OFFICE.

CHARLES J. BAILEY, OF NEWTON, MASSACHUSETTS.

DESIGN FOR A FOOTHOLD.

SPECIFICATION forming part of Design No. 26,532, dated January 12, 1897.

Application filed July 16, 1896. Serial No. 599,446. Term of patent 14 years.

To all whom it may concern:

Be it known that I, CHARLES J. BAILEY, a citizen of the United States, residing at Newton, in the county of Middlesex and State of Massachusetts, have invented and produced a certain new and original Design for Foot-holds, of which the following is a specification, reference being had to the accompanying drawings, forming a part thereof.

Figure 1 of the drawings shows in perspective a foothold of my novel design, and Fig. 2 an under side view thereof.

The leading feature of my design for foot-holds consists of a short sole portion and an attached upturned portion along the sides and toe to form a covering for the fore part of the foot, one of the rear ends of such upturned portion being prolonged to form a long tab or projection, forwardly inclined with relation to and above the main portion of the foothold.

The foothold comprises a sole portion *a* to cover only the fore part of the sole of the

shoe when the foothold is used, and the upper is formed by an attached upturned portion *b*, extending from the toe back to the line *2*. The rear end of the sole is contracted and has connected with and extended upwardly from it a rearwardly-inclined mouthpiece *c*, and the upturned portion is prolonged at one end of its rear ends to form a long tab or projection *c'*, extended upwardly and forwardly inclined above the main portion of the foothold. The junction of the rear ends of the upturned portion and the side edges of the mouthpiece is indicated by the line *2*.

What I claim is—

The design for footholds substantially as herein shown and described.

In testimony whereof I have signed my name to this specification in the presence of two subscribing witnesses.

CHARLES J. BAILEY.
